UNITED STATES PATENT OFFICE.

JOHN P. WEIS, OF BROOKLYN, NEW YORK, ASSIGNOR, BY MESNE ASSIGNMENTS, TO
METROPOLITAN SEWING MACHINE COMPANY, A CORPORATION OF NEW YORK.

BINDING SEWING-MACHINE.

No. 922,646.

Specification of Letters Patent.

Patented May 25, 1900.

Application filed March 26, 1903. Serial No. 149,651.

To all whom it may concern:

Be it known that I, JOHN P. WEIS, a citizen of the United States, residing in Brooklyn, county of Kings, and State of New York, have 5 invented a new and useful Improvement in Binding Sewing-Machines, of which the following is a description.

My invention relates to sewing machines of the type in which the binding and sewing 10 are done simultaneously.

Particularly, my invention relates to mechanism by which bindings may be applied to all kinds of material, whether woven, knitted or otherwise produced, and in which 15 the material and binding may be advanced to and fed from the stitch-forming mechanism simultaneously, evenly and without puckering or stretching the one relatively to the other.

20 My invention is specially useful in binding knit goods or loosely woven fabric, because such materials stretch excessively under the action of the feed and during the application of the binding, the latter being, ordinarily, of closer weave or texture and not liable to stretch. With these conditions of the work, 25 difficulty has been found in mechanically applying the binding evenly and smoothly and in a manner to overcome the tendency of the material and binding to pucker relatively and produce unsightly work.

One of the objects of my invention is to provide a mechanism by which bindings may be applied to all kinds of fabric with facility, 35 rapidity, accuracy and neatness; and by which the tendency of the material and binding to pucker relatively is overcome and prevented.

Another object of my invention is to provide means for controlling the condition of the material and binding as they are being fed to the stitch-forming mechanism; that is to say, operating upon the two, or manipulating them, in such manner as to produce 45 precisely the condition desired at the stitch-making point, thus rendering it possible for the operator to produce and maintain evenness of work during the rapid operation of the machine.

50 It is a further object of my invention to so enlarge the scope and operation of machines of the character stated as to enable them to perform, under the control of the operator, a great variety of work, such as puckering or fulling one piece of material on or relatively

to another; or stretching one piece of material on or relatively to another.

It is a still further object of my invention to provide a means by which any desired length of feed may be obtained during the 60 operation of the machine and by which, after a maximum and minimum length of feed have been determined upon, either one of the two extremes of feed may be obtained instantly and with certainty during the 65 operation of the machine.

Another object of my invention is to provide mechanism for lifting the presser-foot and parts carried thereby; and mechanism for adjusting the feed, which two mechanisms can be actuated by the foot of the operator, thus leaving the hands of the latter entirely free for controlling the fabric in its passage to the stitch-forming mechanism.

Another object of my invention is to provide means by which the feed, carried by the presser-foot, may be thrown out of action and rendered without function, without affecting the operation and functions of the lower feeding mechanism. And another object of my invention is to provide a means by which angular corners can be turned, in binding a piece of fabric or a garment, neatly and perfectly, and by which said corners can be completely stitched.

With the above objects in view, and others which will be hereinafter noted, my invention consists in the parts, elements, features and combinations hereinafter described and claimed.

In the drawings: Figure 1 is a perspective view of the front end of a machine showing my invention, the cloth-plate being removed; Fig. 2 is a vertical section approximately on the line 2--2 of Fig. 1; Fig. 3 is an end elevation of that part of the machine below the presser-bar; Fig. 4 is a perspective showing the presser-foot and the feed-foot combined, and enlarged; Fig. 5 is a detail perspective showing the parts of Fig. 4, separated and in position for assembling; Fig. 6 is an enlarged view of the end of the folding-guide showing the disposition of the bar 72; Fig. 7 is an end elevation of the parts shown in Fig. 6, showing also the material in the 105 guide and under the end 74, of the bar 72; showing also a section of the throat-plate and the depression thereof in which lies the extension 67, of the guide 71; Fig. 8 is a top plan showing the throat-plate, the folding 110

guide and a section of the cloth-plate; Fig. 9 is a vertical section on the line 8—8 of Fig. 8; Fig. 10 is a section of the throat-plate on the line 9—9 of Fig. 8; Fig. 11 is a front end elevation of the throat-plate; Fig. 12 is a front end elevation of the folding guide in position on the cloth-plate; Fig. 13 is a detail view showing the disposition of the treadle, knee-rest and connecting parts; Fig. 14 is a front elevation of the parts shown in Fig. 13; Fig. 15 is a plan view of a section of the work showing the corner as having been turned and stitched down; Fig. 16 is a similar view showing the corner in the process of being turned with the instrument 91, in position; Fig. 17 is a sectional view portraying the relative position of the presser and feed feet and the work; Fig. 18 is a sectional view showing in full lines the binding after the folds have been turned, and in dotted lines showing the binding before the folds have been made, but after the body material has been turned preparatory to laying the corners of the binding; and Fig. 19 is a plan of the neck and body portion of a garment portraying the angular corner and the character of work accomplished.

The main frame is indicated by 1; and 2, is the driving shaft; 3, the needle-bar which is caused to reciprocate vertically in the head of the machine. The stitch-forming mechanism has not been illustrated because the same forms no part of my invention and because it is desired to clearly portray the important features of my invention.

The main-shaft of the machine carries at its forward end a slotted disk 4, to which is adjustably connected, in usual manner, the connecting rod 5, the outer end of which is connected to the outer end of a short shaft 6, carried by the feed-rocking frame 7, suitably journaled in the bed-plate of the machine. The short shaft 6, of the rocking frame 7, has fixed thereto the feed-bar 8, which carries at its outer end the feed-dog 9, which may be connected adjustably thereto in any suitable manner. The feed-bar 8, has a guide-way therein in which reciprocates the feed-bar 10, and which is given its feeding movements by mechanism hereafter noted. The two bars 8 and 10, are caused to have vertical movements by the same means, said means being an eccentric 11, on the main-shaft, embraced by the bottom of the bar 8, and an angular arm 12, carried thereby.

The bar 10, carries a feed-dog 13, which is vertically adjustable in a socket in the end of the bar 10, by means of a screw 14. The same adjusting means are provided for the dog 9. The feed movement of the dog 9, is adjustable by means of the connection of the arm 5, with the disk 4, on the end of the shaft 2.

The feed movements of the dog 13, which may be termed the main-dog because it oper-

ates upon the main fabric or article to which the binding is applied, are produced by means of the lever 15, pivoted at its lower end to the bed-plate of the machine, or a bracket thereof, and connected at its upper end pivotally with the bar 10, the connection being provided by means of a screw 16, carrying a shoe or block 17, sliding in a longitudinal slot 18, in the lever 15, and said screw entering the bar 10, the shoe or block pivoting or swiveling on the screw. The feed movements of the main-bar 10, are regulated by means of the three-armed lever 19, journaled at its angle to the short shaft 6, carried by the rocking frame 7. One arm 20, of the lever, is provided with a pivotally connected shoe 21, which embraces and slides longitudinally on the lever 15. The arm 22, of the lever depends below its pivot and has connected thereto an angular bracket 23, rendered adjustable by means of the screw 24, extending through a longitudinal slot 25, in the bracket, and tapped into the arm 22, and the head of which screw clamps the bracket to the arm. A pin 26, is connected to the arm 22, and projects into the slot 25, of the bracket and acts as a limit for the adjustment of the latter in one direction and also prevents the bracket from swinging on its binding screw. The bracket has the angular portion 27, carrying a lug or stop 28, which contacts with the web portion of the rocking frame 7. The arm 22, is also provided with an angular portion 29, carrying an adjustable stop or screw 30, which may contact with the opposite side of the web of the rocking frame 7, and is held in adjusted position by jam-nut 301. The third arm 31, of the lever has connected thereto, in any suitable manner, the chain 32, or other suitable device, which at its lower end, is connected to the treadle 33. At some point between its ends, the chain, or other connection, is provided with a coiled spring 34, which when pressure is applied to the treadle causes the chain to transmit a yielding pull upon the arm of the lever 19, and also prevents the vibration of the latter, caused by the rocking frame 7, during the operation of the machine, from being transmitted to the foot on the treadle, as hereinafter noted. The interposition of the spring also takes up any slack in the chain which may occur between its ends and prevents the chain from rattling during the rapid operation of the machine. To still further prevent rattling and to take up the slack in chain 32, the spring 35, connected to the chain and frame of the machine, is provided. Normally, the lever 19, is held with its arm 20, depressed by means of a spring 20^x, that is to say, the spring keeps the stop 28, in contact with the web of frame 7, whatever the initial adjustment may be, and after the adjustment has been altered by depressing the arm 31, of lever 19, and the lever has been re-

leased, the spring will return the stop 28, into contact with the web of the rocking-frame.

The feed-bar 8, has connected thereto a vertically adjustable bracket piece 36, the same being rendered adjustable by means of the longitudinal slot 37, therein and the screw 38, passing therethrough into the bar. At its upper end the bracket 36, has pivotally connected, or hinged, thereto an arm 39, the joint 40, between the two being close and tight in order that when said arm is turned down out of the way, below the cloth-plate, the same will be prevented from moving and from rattling against the cloth-plate, the feed-bar or any other adjacent part of the machine, during the operation of the latter. At its upper end the arm 39, is provided with an aperture or screw-threaded bore 41, coinciding with the smooth bore 42, in the rear end of an upper feed-foot 43, pivotally and slidably connected with the presser-foot 44, by means of a screw 45, extending transversely through the presser-foot and an elongated slot 46, in the feeding-foot. The clamping screw 45, is provided with an enlarged head, a smooth stem portion 47, and a reduced screw-threaded portion 48, and detachably connects the arm 39, with the rear end of the feeding-foot. The forward end of the foot is provided on its bottom with serrations or feed-teeth 49. The upper feeding-foot operates in an elongated slot 50, in the short portion 51, of the presser-foot. Said presser-foot 44, is also provided with the long portion 52, which bears upon and coöperates with the main feed-dog 13. The presser-foot is provided with three vertical bars 53, 54, 55, extending longitudinally thereof and providing between the same the slots or grooves 56, 57. In the groove 57, is suitably secured the downwardly depending lug 58, of the socket 59, which surrounds and is clamped to the presser-bar as usual. In the groove 56, the feeding-foot 43, slides and rocks on the screw 60, passing through the bar 53, slot 46, and into the bar 54. The feeding-foot operates oppositely to a smooth and solid part 62, of the throat-plate 61, and close to and beside the needle apertures in the throat-plate and the presser-foot. The rear portion of the short part of the presser-foot coöperates with the auxiliary feed-dog 9.

The throat-plate of the machine is provided with the elongated slot 63, for the reception of the lower feed-dogs, and as before stated with the solid portion 62, for receiving the pressure of the upper feed-foot. In advance of the said solid portion and the needle aperture of the throat-plate, the latter is provided with a depression 64, and with a side flange 65, the depression receiving the bottom of an elongated portion 67, of the binding-guide 66, and the flange re-

ceiving the side of such portion of the guide, thus keeping the latter firmly in proper position and permitting the said elongated portion of the guide to reach and operate close to the needle aperture in the throat 70 plate. The binding guide includes the supporting plate 68, which is secured to the cloth-plate of the machine by means of the collar and fastening screw 69. Said plate has secured thereto a suitable strip-guide 75 70, and in advance thereof is provided with a curved strip-guide 71, which leads in the binding and properly turns the same upon the edge of the work. The lower portion of the curved strip-guide at its base is provided with the forwardly extending portion 67, which lies in the depression and against the flange 65, of the throat-plate, close to and just in advance of the needle aperture as described. Extending parallel with the elongated portion of the guide, is a wire or small bar 72, secured at one end to the guide in any suitable manner, and at its forward end being bent at an angle to its main part as at 73, and extending in front of the elongated portion 67, of the guide and between the forward end of the latter and the needle aperture in the throat-plate. The free end of the angular portion of the bar is bent downwardly slightly, and is beveled from the top 95 to the bottom to provide the sharp edge 74, which lies just above the path of travel of the lower edge of the doubled binding strip and extends longitudinally of said path, viz., the sharp edge 74, of the bar extends 100 substantially parallel with the edge of the binding material. The function of this construction will be hereafter explained. The forward end of the supporting plate 68, is extended at 75, and provided with a vertical 105 wall 76, affording a guide for the edge of the material or work.

The presser-bar 59, is provided with the laterally projecting lug or arm 77, upon which bears the spring 78, which normally 110 tends to hold the bar down to its work, and the pressure of which spring is regulated by the adjusting-screw 79, and jam-nut 80, extending through the frame of the machine and bearing upon said spring. A lever 81, pivoted to the arm of the machine, has its forwardly extending arm 82, located under the lateral arm 77, of the presser-bar, said forward arm 82, being normally held out of contact with said lateral arm of the presser-bar by means of the coiled spring 83, secured to the arm of the lever and to any stationary part of the machine. The rear arm of the lever is connected by means of a chain 84, or other medium, with the arm 85, of a rock-shaft 86, secured to the under side of the table which supports the machine, and the forward end of which rock-shaft is provided with a smooth bore through which extends a rod or arm 87, adjustable in said bore by 130

means of a screw 88, tapped into the end of the shaft. The arm 85, may be rendered adjustable in like manner. The other end of rod 87, is pivotally connected to a link 89, which in turn is pivotally connected to the knee-rest 90, suitably pivoted to the table and depending in convenient position for operation. The depression of lever 81, is regulated by the adjustable stop 81^x, passing through the frame of the machine,—see Fig. 1.

A foot-treadle, located beside the foot-treadle 33, which operates the feed-adjusting mechanism, controls a clutch-mechanism coöperating with a prime-mover which conveys power for operating the machine, as is usual and unnecessary to illustrate.

The operation of my machine is as follows: Primarily, it should be understood that one of the principal objects of my machine, comprising the differential feeding mechanism and the binding mechanism, is to apply a binding to a piece of material, or a garment, smoothly and evenly, and without puckering or stretching the binding and the material relatively. Another of the principal objects is to turn an absolutely angular corner on the work or garment with the binding; that is to say, in turning corners or angles it has heretofore been a difficult matter to turn an angular corner evenly and perfectly, the normal tendency in turning corners, in applying the binding, being to round the corners and to stretch or turn under or, in some other manner, distort the binding on the material. This obviously, is objectionable, makes unsightly work and reduces the value of the finished article.

By the mechanism which I have described above the binding can be applied evenly to the material, without gathering or stretching the one relatively to the other, and angles can be neatly turned and the corners perfectly stitched down.

It should be noted that the main feed-bar 13, coöperates with the main portion 52, of the presser-foot in clamping and feeding the body-material; and that the auxiliary feed-dog 9, coöperates with the portion of the presser-foot in rear of the short foot 51, for feeding the binding in rear of the needle aperture; and that the upper feed-foot operates upon the upper fold of the binding and co-
operates with the smooth portion of the throat-plate thereunder. The edge of the body material is placed in the channel of the binding-guide and is guided by the vertical portion 76, of the plate 68. The binding is led through the guide 70, and then into the folder or guide 71, its lower fold being fed out of the end of the extension 67, and under the edge 74, of the bar 72, and between the extension 73, of said bar, and the throat-plate of the machine. The throw of the auxiliary feed-dog is properly adjusted by suitably

placing the connection between the arm 5, 65 and the disk 4; and the throw of the main-feed dog is suitably regulated, as to its initial throw, by adjusting the bracket 23, upon the depending arm 22, of the lever 19. Ordinarily, the main-dog 13, will be caused to 70 have a greater throw than the auxiliary dog; and if at any time during the operation of the machine, it is desirable to make the throw of the two-dogs uniform the treadle 33, would be depressed, thus depressing arm 31, of lever 19, elevating arm 20, of said lever and causing the pivotal connection of said arm with the lever 15, to coincide with the pivotal connection between the lever 15, and the main-bar 10. Obviously, the throw of the 80 dog 13, relatively to the throw of the dog 9, can be varied according to the position of the shoe 21, on the lever 15; and extremes of adjustment may be quickly and positively obtained by setting the adjustable stops 28, 85 and 30, in predetermined positions, and such extremes of adjustment may be obtained during the rapid operation of the machine, and without affecting the stitch-forming mechanism, by depressing the arm 31, of the 90 lever 19, as previously described. The spring 34, is interposed in the length of the chain 32, for the purpose, principally, of avoiding the vibration of the rocking frame 7, being transmitted, through the lever 19, 95 and the chain 32, to the treadle 33, and to the foot of the operator which is constantly in contact therewith. Rattling of the chain on the treadle 33, is avoided by taking up the slack by means of the spring 35.

The knee-rest 90, is conveniently located for actuation by a side movement of the knee of the operator, such movement being transmitted through the link 89, and rod 87, to the rock-shaft 86, and thence through the 105 arm 85, and chain 84, to lever 81, thus elevating its short arm 82, and lifting the presser-foot 44, from the work. This elevation of the presser-foot may be a great convenience at any time during the progress of sewing, and 110 is necessary, of course, in placing the work to begin sewing. The knee-rest mechanism affords a convenient and ready means for lifting the presser-foot and for leaving the hands of the operator free to properly manipulate the different parts of the work and attend to other necessary things above the work-plate. During the operation of applying the binding to the body-material, and when a corner or turn is reached, it is necessary to stop the machine with the needle out of the work, loosen the thread to provide sufficient slack to enable the needle to next descend at the point *a*, Fig. 15, which point is reached by first elevating the presser-foot 120 and then turning the work at an angle to its former position and then drawing said work toward the operator sufficiently. Just prior

to turning the work, however, the instrument 91, is inserted in the fold of the binding which latter is, by said instrument, folded over upon the body material and its own upper fold portion, as shown in Fig. 16, at *d*, wherein the dotted line represents the upper fold of the binding before the corner is completed and the solid lines represent the condition of the upper fold of the binding after the corner has been completed and preparatory to stitching the same down. These operations are essential to the proper turning of the angular corner, and while the same are in progress, the edge of the lower fold portion of the binding engages the edge 74, of the extension 73, of the bar 72, at the point *e*, Fig. 18, and prevents said edge of the fold from being dragged back out of place; and the turning of the body-material, as above described, causes the latter to pass over said extension 73, and double the binding upon itself and thus automatically form the fold *b*. The binding and material are now in readiness to be stitched together in proper manner, and a perfectly angular corner has been produced by the manipulation stated, as clearly shown in Figs. 15, 16 and 18. The stitching now begins at *a*, in Fig. 15, and securely fastens both folds of the binding strip at the corner, preventing the same from being pulled or strained apart.

It may be observed that all the difficulty, heretofore experienced in turning angular corners, has resulted from the lack of some means for manipulating the binding on the bottom of the work, because the natural tendency of the binding is to curl and slide laterally away from the edge of the body-material and transversely of the folding guide. The extension 73, of the bar 72, prevents the curling, or sliding, or any lateral movement of the lower fold of the binding, as will be obvious. As shown in Fig. 17, the upper feed-foot operates directly upon the binding at the corner quite a distance in front of the needle and, as the machine is started, immediately feeds the binding, at the fold; at the same time the body material is fed; thus preventing any drag upon the binding and the stretching or distorting of the fold.

It should be noted that in sewing the binding to garments, or other work, of the character shown in Fig. 19, it is necessary to manipulate the feeding mechanism so that, in sewing along the straight edge *e*, all the feed-dogs shall have the same speed, this being accomplished by depressing the treadle 33, and placing the connection 21^x, coincident with the connection 16. But, when the corner has been turned, as above described, and the sewing is begun along the curved edge *f*, it is necessary to cause the main feed-dog 13, to feed faster than the auxiliary dog

9 and the foot 43, which is accomplished by 65 releasing the treadle 33, and allowing the arm 20, to be returned to the predetermined position by the spring 20^x.

The connection between the feed-foot and the bar 8, is removable as previously stated, this construction enabling the feed-foot to be thrown out of operation at any time it is desired to use the machine for any purpose for which said feed-foot would not be essential. The adjustable connection of the feed-foot 70 with the bar 8, enables the foot to be regulated vertically and its pressure or grasp upon the work adjusted at will. Moreover, when very heavy work is being operated upon, the elevation of the presser-foot would 75 lift the feed-foot too high for contact with and proper operation upon the binding. Hence, the adjustment of the plate 36, would 80 be necessary. The pivotal connection between the arm 39, and the plate 36, enables 85 the said arm to be turned down below the cloth-plate,—when the feed-foot is not in operation,—and the tight fit between the arm and the plate, previously described, prevents said arm from rattling against adjacent 90 parts of the machine during the operation of the latter. Obviously, the vertical adjustment of the plate 36, will regulate the throw of the feed-foot and the latter may have a movement different in extent from the auxiliary feed-dog 9.

Having thus described my invention what I claim and desire to secure by Letters Patent is:

1. A sewing and binding machine, comprising stitch forming mechanism, feeding mechanism, and binding mechanism; the feeding mechanism including lower, differential feed-dogs for operating upon the body and binding materials, respectively, and an upper feed-foot for operating upon the binding material, and means for actuating the said dogs and foot for positively advancing the materials; and the binding mechanism including means for preventing the binding from curling.

2. A sewing and binding machine, comprising stitch forming mechanism, feeding mechanism, and binding mechanism; the feeding mechanism including a plurality of feed-devices for operating upon different portions of the materials, means for actuating the said devices for positively advancing the materials; and means for regulating the movements of said devices relatively during the operation of the machine and without affecting the stitching; and the binding mechanism including means for preventing the binding from curling.

3. A sewing and binding machine, comprising stitch forming mechanism, feeding mechanism, and binding mechanism; the feeding mechanism including devices for op-

erating upon the top and bottom of the materials, and means operable during the running of the machine for controlling said devices whereby to relatively differentially operate the same and positively advance the materials; and the binding mechanism including means for preventing the binding from curling.

4. A sewing and binding machine, comprising stitch-forming mechanism, feeding mechanism, and binding mechanism; the feeding mechanism including a feed-device for operating upon the body-material, independent devices for operating upon the bottom and top, respectively, of the binding in a path different from that in which the feed-device operates, and means for actuating said several devices for positively advancing the several materials concurrently; and the binding mechanism including means for preventing the binding from curling.

5. A sewing and binding machine, comprising a feeding mechanism including three independent work-feeding devices for operating upon the top and the bottom of the binding and upon the body-material, respectively; means for giving to said devices their vertical movements; common means for imparting the feed-movements to two of said devices for advancing the work past the stitching position; means for imparting the feeding movement to the other of said devices; and a binding guide.

6. A sewing machine comprising a plurality of feeding devices, two of said devices being located below the work-plate for operating upon the binding and body-material, respectively and one of said devices being located above the work-plate, for operating upon the binding means for actuating the several feeding devices, means for lifting one of said devices bodily from contact with the work; and a binding guide.

7. A sewing and binding machine, comprising stitch forming mechanism, a feeding mechanism, binding mechanism, and slotted throat-plate having a depression in advance of the stitching point; the feeding mechanism including feed-dogs operating through the slotted throat-plate one behind and the other at the side of the stitching point, and means for actuating said dogs at different speeds to positively advance the work; and the binding mechanism including a guide located in the depression of the throat-plate; whereby the work and binding may be fed at speeds such that the latter will be applied to the former uniformly and smoothly and the binding may be advanced to the stitching point without drag and in the plane of the throat-plate at the stitching point.

8. A sewing and binding machine comprising a differential feed-mechanism; a throat-plate through which the dogs of the

feed-mechanism operate, said throat-plate having a depression, and in rear thereof a solid portion; a binding-guide having a portion lying in the depression of the throat-plate and close to the feed-dogs; and an upper feed - foot operating oppositely to the solid portion of the throat-plate; and means for operating the said feed-foot.

9. A sewing and binding machine comprising a differential feeding-mechanism; a binding mechanism; a presser-foot mechanism; a supplemental feed-foot; and means whereby said feed foot may be lifted at will from the work by devices actuated from below the table.

10. A sewing and binding machine, comprising a binding-mechanism; a feeding-mechanism for positively advancing the work and binding, and a presser-foot mechanism, coöperating with the feeding mechanism the binding-mechanism having an elongated portion lying close beside the feeding-mechanism and extending under the presser-foot up close to the stitching point, and having in advance of said elongated portion a device for preventing the curling or lateral movement of the binding at the stitching point.

11. A sewing and binding machine, comprising a feeding mechanism having a plurality of dogs operating at different speeds, a presser-foot having portions coöperating respectively with the several dogs, a supplemental feed-dog carried by the foot, means for actuating said supplemental dog, and a binding guide coöperating with the feeding mechanism.

12. A sewing and binding machine, comprising a differential feeding mechanism including a device for operating upon the body-fabric at one side of the stitching point and for advancing said fabric; an independent device operating upon and advancing the binding in rear of the stitching point; and another independent device operating upon and advancing the binding on the side of the stitching point which is opposite that on which the body-fabric is engaged by its feeding device; and a binding guide coöperating with the feeding mechanism.

13. A sewing and binding machine comprising feeding mechanism including a device operating upon and feeding the body-fabric in advance of, up to, and on one side of the stitching point; an independent device operating upon and feeding the binding in rear of the stitching point; and another independent device operating upon and feeding the binding on the side of the stitching point which is opposite that on which the body-fabric is engaged by its feeding device; and a binding mechanism coöperating with the feeding mechanism.

14. A sewing and binding machine com-

prising a differential feeding mechanism having portions coöperating with and operating upon different portions of the work to be advanced; a presser-foot having portions coöperating respectively with the different portions of the feed, and a binding device having a portion located close to the feeding mechanism and extending under the presser-foot up close to the stitching point so as to deliver 10 the binding at the stitching point free of drag or tension.

15. A sewing and binding machine comprising a differential feeding mechanism having a plurality of independent feeding-devices operating in parallel paths and operating upon different portions of the work to be advanced; a presser-foot having independent parallel portions coöperating respectively with the several feeding-devices, and a binding-device, for guiding and applying a binding to the work, having means for engaging one edge of the binding after leaving the binding-device to prevent the same from curling at the stitching point.

25 16. A sewing and binding machine comprising a feeding mechanism having a plurality of dogs, means for regulating the speed of the dogs relatively, a presser-foot having portions coöperating with the respective dogs, a throat-plate through which the dogs work, and having a solid portion about its needle aperture, a supplemental feeding-foot coöperating with the solid portion of the throat-plate, and a binding guide located in

advance of the stitching point and close to 35 one of the feed-dogs.

17. A sewing and binding machine comprising stitch-forming mechanism and feeding mechanism, the feeding mechanism including lower, differential feed-dogs for operating upon the body and binding materials, respectively, and an upper feed-foot for operating upon the binding material, and means for actuating the said dogs and foot for positively advancing the materials; and a binding mechanism arranged in advance of the stitching mechanism to present the binding to said mechanism in coöperation with the body material.

18. A sewing and binding machine comprising stitch-forming mechanism and feeding mechanism including a feed-device for operating upon the body material, independent devices for operating upon the bottom and top, respectively, of the binding in a path 55 different from that in which the feeding-device operates, and means for actuating said several devices for positively advancing the several materials concurrently; and a binding mechanism coöperating with the feeding 60 mechanism.

In testimony whereof I have hereunto signed my name in the presence of two subscribing witnesses.

JOHN P. WEIS.
